United States Patent Office.

CHARLES N. BRUMM, OF MINERSVILLE, PENNSYLVANIA.

Letters Patent No. 88,126, dated March 23, 1869.

IMPROVED MEAT-CHOPPER.

The Schedule referred to in these Letters Patent and making part of the same.

To all whom it may concern:

Be it known that I, CHARLES N. BRUMM, of Minersville, in the county of Schuylkill, and in the State of Pennsylvania, have invented certain new and useful Improvements in Meat-Chopper; and do hereby declare that the following is a full, clear, and exact description thereof, reference being had to the accompanying drawings, and to the letters of reference marked thereon.

The nature of my invention consists in the construction and general arrangement of a "meat-chopper," which will be hereinafter fully set forth.

In order to enable others skilled in the art to which my invention appertains, to make and use the same, I will now proceed to describe its construction and operation, referring to the annexed drawings, which form a part of this specification, and in which—

Figure 1 is a side elevation of the machine;

Figure 2 is a side view of certain gearing used therein;

Figure 3 represents side views of the cam-wheel causing the oscillating motion of the choppers;

Figure 4 is an end view, in section, of the chopper; and

Figure 5 is a vertical section through the centre of the block.

A represents a round block of wood, generally denominated a butcher's block.

A metal frame, or bent bar, B, is secured to said block, forming two standards, with cross-bar on top, as shown in fig. 1.

In the centre of the block A is placed a small metal block, C, with a hole through its centre, and on its upper side, around the centre hole, it has a circular rounded projection, a, which forms the bearing for a nut, b, which is provided with a circular flange, c, fitting into the centre of the projection a.

Through the nut b passes the central shaft D, said shaft being, at its lower end, provided with screw-threads fitting into the nut b.

The shaft D passes upward through a hole in the upper portion of the frame B, thus having its bearings in said frame, and in the nut b.

Another nut, d, is placed on the screw-end of the central shaft D, above the nut b, and by the use of these two nuts, the shaft D can be raised or lowered at will.

The upper end of the shaft D, above the frame B, is square, and a cog-wheel, E, is fitted on the same, in such a manner that the shaft may, at any time, be raised or lowered, without interfering with said wheel.

The wheel E gears into a worm, F, which has its bearings in ears, or lugs on the side of the frame B.

One end of the shaft, for the worm F, is provided with a wheel, G, which has a limited number of notches, e e, in its outer edge, at equal distances from each other.

A horizontal shaft, J, which has its bearings in the side of the frame B, and in an ear, K, projecting down-

ward from the upper portion of said frame, is provided with a three-pronged star or wheel, I, which gears into the notches of the wheel G, so that when said shaft J is turned by means of its crank L, motion is, through the worm F and cog-wheel E, communicated to the central vertical shaft D.

The shaft D is slotted at a suitable point above its lower screw-end, and in this slot the beam, or lever M is pivoted. This lever is crooked, forming an angle in the centre, and pivoted at the angle-point, as shown in fig. 1.

To the ends of the lever M are secured solid cutter-blades N N, each of which carries two knives, O O.

On the shaft D, under the lever M, is placed a light metal frame, or slotted guide, P, through which the knives O O pass, said guide preventing the meat from adhering to the knives.

The lever M obtains an oscillating motion from a cam, R, which is provided with three teeth, f f, and secured to or forming part of a sleeve, S, which is placed around the central shaft D, and at its upper end provided with a mitre-wheel, T, which gears into and rests on another mitre-wheel, V, secured to the inner end of the shaft J.

The mitre-wheel T is secured to a nut, U, which is screwed on to the upper end of the sleeve S, so that the cam R may be raised or lowered, to correspond with the raising or lowering of the central shaft D, as above described.

It will thus be seen that the turning of the crank L contributes motion to both the sleeve S, and to the shaft D, but in opposite directions.

The cam R, by means of its teeth f f, forces the ends of the lever M, with its knives, alternately up and down at the same time as the central shaft D carries the lever and knives around, so that said knives may act upon all parts of the meat placed on the block A.

The upper edge, or surface of the lever M is bevelled, and it is on this bevel-surface that the teeth of the cam R operate.

By means of the angle, or crook in said lever, or beam, I get impetus at the end of that side of the beam that is down, while, as it approaches that position, it gets further from the centre, or fulcrum, thereby gaining leverage, while the other end of the beam, which is up, is nearer to the centre, or fulcrum, and of course losing leverage as it approaches that point.

These ends, of course, only begin to gain and lose leverage after they pass the centre, or balancing-point.

As the block A wears away, the chopper can be lowered, without altering the whole machine, by means of the two nuts b d, at the lower end of the central shaft D, and the jam-nut U, next to the mitre-wheel T, on the sleeve S.

The teeth on the cam R may be of different construction. In fig. 3, I have shown three different-shaped teeth, f¹, f², and f³.

The tooth f¹ is formed with an even plane on the working-surface, the same as the teeth shown in fig. 1,

and will produce the same power and speed of the beam at every given point of the plane, or working-surface of the tooth.

The tooth f^2 , formed with a concave working-surface, will have more power, but, of course, will produce less speed at its base, while it will have less power, and produce more speed as it approaches its point, owing to the fact that the angle of the plane of the tooth is less at its base than toward its point.

The tooth f^3 , formed with a convex working-surface, will produce the opposite result from the concave tooth.

Having thus fully described my invention,

What I claim as new, and desire to secure by Letters Patent, is—

1. The combination of the toothed cam R and sleeve S with the lever M, pivoted, as specified, for producing

an oscillating as well as a revolving motion, by means of the worm-gearing, substantially as specified.

2. The combination of the slotted shaft D, oscillating beam M, with its knives O O, and guide P, with the cam R and sleeve S, all constructed and operating substantially as and for the purposes herein set forth.

3. The arrangement of the shaft J, mitre-wheels V and T, with the three-pronged star I, notched wheel G, and worm F, for the purpose of producing the requisite oscillating and rotary motion of the beam M, substantially as herein set forth.

In testimony that I claim the foregoing, I have hereunto set my hand, this 3d day of February, 1869.

Witnesses: CHARLES N. BRUMM.

LEOPOLD EVERET,
WM. S. MOORHEAD.
